THE NORRIS PETERS CO. PHOTO-LITHO. WASHINGTON, D. C.

UNITED STATES PATENT OFFICE.

JOHN C. TURNER, OF DAYTON, OHIO, ASSIGNOR TO THE JOHN C. TURNER NOVELTY CO., OF DAYTON, OHIO, A CORPORATION OF OHIO.

DRAWBRIDGE.

1,297,044.

Specification of Letters Patent.

Patented Mar. 11, 1919.

Application filed June 7, 1917. Serial No. 173,323.

To all whom it may concern:

Be it known that I, JOHN C. TURNER, a citizen of the United States, residing at Dayton, in the county of Montgomery and State of Ohio, have invented a new and useful Improvement in Drawbridges, of which the following specification is a full disclosure.

This invention relates to toys and it proposes an apparatus simulating a drawbridge.

One object is to render available a simple construction adapted to form the basis of a toy and which is an imitation of a drawbridge adapted normally to rest in "open" position and to "close" at a predetermined station in the approach of a car from either direction.

Another object is to devise a simple toy drawbridge which is held by a latch against the spring pressure in an "open" position and which is released by car-action to swing into closed position and permit the passage of the car.

Other objects are in part obvious from the annexed drawings and in part indicated in connection therewith by the following analysis of this invention.

This invention accordingly consists in the features of construction, combination of parts and in the unique relation of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:—

Figure 1 is a plan of one embodiment of this invention. Fig. 2 is a side elevation thereof; both views showing the drawbridge in its latched open position ready to be closed by the approach of a car.

Continuing with reference to the drawings, A indicates the drawbridge proper which consists of a bridge element formed of sides 1 and 2 preferably cut and ornamented to imitate trestlework. These sides are shown connected by a plurality of ties 3, 4 and 5; the latter serving also as a sup-

port for the pivot of the drawbridge. This tie 5 rests on a post 6 upstanding from the base B of the drawbridge, and a suitable pin or axle 7 extends downwardly from the tie 5 into a socket 8 in the pillar 6 and a coiled spring 9 encircles the pin 7 and tends normally to rotate the drawbridge in the direction of the arrow 10 so as to swing or snap it into closed position. A stop 11 uprises from the base B and limits the movement of the drawbridge by being impacted by the side wall 2 thereof; thus determining the "closed" position of the drawbridge.

The base B has two side wings 12 and 13 in alinement and a lateral wing 14 which carries a latch device. Each of the side wings 12 and 13 are provided with standards 15 and 16 upon which are supported the ends of track sections C and D so that when the drawbridge is in its closed position, the rails 17 and 18 will match or register with the rails 19 of the drawbridge. By means of suitable devices not herein shown, the track sections C and D may be tilted upwardly and downwardly about the standards 15 and 16 as fulcrums so as to determine the direction of movement of a suitable gravity car here diagrammatically represented by E.

Each of the track sections C and D are provided with means whereby the gravity car E is enabled to act on a latch normally holding the drawbridge in its open position so as to cause the drawbridge to swing under the action of the spring 9 into its closed position in anticipation of the approach of the gravity car E. This instrumentality comprises a latch member F pivoted at a to the wing 14 of the base B and normally held by a spring e against a stop-pin k. A beveled tongue or latch proper m projects from the part F and is adapted to catch against the drawbridge to retain it in its open position, the small spring e being of sufficient strength for that purpose. The tongue m is carried by a socket in the part F and is spring-pressed outwardly and is provided with a bevel so that the drawbridge may manually be swung back from its closed into its open position and retained in the latter. In order

that the latch F may be withdrawn to permit the drawbridge to swing into its closed position, two cords n and r respectively run around a pulley s and connect with the latch member F so that a pull on said cords will swing said latch member away to one side 110

and permit the drawbridge to close. The cords *n* and *r*, respectively pass around pulleys *t* and *w* and then extend to the track sections *C* and *D*, respectively to connect with operating mechanisms arranged in conjunction therewith. Since these mechanisms are identical in each instance, it will suffice to describe the one associated with track section *C*. A standard *b* provides a part *c* carrying a pivot *d* supporting a weighted trip *f*. The cord *n* extends around pulleys *h* and *i* carried by a post *o* and is attached to the upper end of the trip *f*. Now, when the car *E* comes along, its lower portion *v* hits the trip *f* and swings it over in such a direction as to exert a pull on the cord *n* with the effect that the latch *F* is pulled away and the drawbridge *A* is permitted to swing into registry with the track sections *C* and *D*. The car then proceeds on its way across the drawbridge and over and along the track section *D* and when it reaches the counter part trip *f'* it merely swings it out of the way without pulling the cord and after the car has passed the trip *f'* then returns to normal. The child then swings the drawbridge *A* manually back to its open position and relatches it in place.

Without further elaboration, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus revealed my invention, I

claim as new and desire to secure by Letters Patent of the United States:—

1. A toy comprising a draw-bridge base and track sections; a drawbridge pivotally mounted on said base and spring-pressed into registry with said track sections; a latch adapted to retain said drawbridge in an open position; and means for enabling an approaching car to operate said latch to release said drawbridge and permit it to swing into its closed position. 45 50

2. A toy combining a first track section; a second track section spaced therefrom; a drawbridge pivoted to swing from an open position into a closed position bridging said space; means resiliently urging said bridge into its closed position; a latch adapted to retain it in its open position; a trip located at one of said track sections to be actuated by an approaching car; and a connection extending from said trip to said latch whereby the drawbridge will swing into its closed position upon the approach of a car. 55 60

3. A toy combining a first track section; a second track section spaced away therefrom; a pivoted drawbridge occupying an intervening position and normally spring pressed into its closed position; latch means for retaining the drawbridge in its open position; an automatic trip mechanism arranged in conjunction with each of said spaced track sections whereby a car approaching in either direction will operate said latch to release said drawbridge. 70 75

In witness whereof, I hereunto subscribe my name, as attested by the two subscribing witnesses.

JOHN C. TURNER.
